UNITED STATES PATENT OFFICE.

JOHN HENRY HETTINGER, OF BRIDGETON, NEW JERSEY.

TOY.

No. 884,387.

Specification of Letters Patent. Patented April 14, 1908.

Application filed October 15, 1907. Serial No. 397,479.

To all whom it may concern:

Be it known that I, JOHN HENRY HETTINGER, a citizen of the United States, residing at Bridgeton, in the county of Cumberland and State of New Jersey, have invented 5 certain new and useful Improvements in Toys, of which the following is a specification.

This invention relates to amusement devices or toys and consists in the novel construction and arrangement of parts as herein-after shown and described.

The object of the invention is to provide a toy adapted to be placed upon a table or other firm, level foundation and having attached thereto a ball possessing a certain amount of resiliency so that it will rebound from a solid surface, the said ball having a series of indentations, any of which are adapted to intersect with the upper portion of the 20 device at such times as the object of the toy is attained.

In the accompanying drawings:—Figure 1, represents a side elevation of the device, partially in section, the ball being shown as resting on the same level. Fig. 2, is a similar side elevation showing a ball positioned on the apex of the pedestal.

The toy comprises a semi-spherical shaped base 1, which may be made of any suitable 30 material, either integral or joined in sections as indicated more particularly in Fig. 1.

To the upper part of the base is attached the concave end of a standard 3, extending upward through the flanged member or 35 guard 2, of approximately the same diameter as that of the base and continuing as at 4, terminates in the angular cone shaped member 5.

Mid-way in the vertical member 3, is a 40 groove 6, to which is secured one end of an elastic cord 7, the other end being securely attached in any preferred manner to the ball 8, which is provided with a plurality of indentations 9, corresponding in shape to the angular, coned top 5, of the toy.

In operation the ball is thrown in the air to

the limit of the elastic cord by which, and the effect of gravity, it is returned with considerable force to the level surface on which the toy is positioned and rebounding from the 50 said level surface, may be caught on the apex 5, the same entering any of the numerous indentations with which the ball is provided which constitutes the manner in which the toy is used.

The purpose of the guard 2, is to compel 55 the ball to pass at a considerable angle in order to gain its position.

In use the standard may either remain stationary or it may be grasped by the hand of 60 the player in an effort to impale the ball on its point.

Modification as to the relative proportion 65 of parts, lengths of cord and the like may be made without departing from the invention, which having been thus described,

What I claim as new and desire to secure by Letters Patent is:

As a new article of manufacture, a toy 70 comprising a hollow semi-spherical shape centrally apertured base, a pedestal having a concave lower end secured on the convex surface of said base over said aperture by a screw passing through said aperture from the inside into said pedestal, the upper end of 75 said pedestal being pointed, a circular guard arranged on said pedestal adjacent its upper end, having a flat upper surface, said pedestal being provided with an annular groove between the base and guard, an elastic cord secured in said groove, and a ball carried by the free end of said cord and provided with a plurality of indentations corresponding in shape to the point of said pedestal.

In testimony whereof I have signed my 85 name to this specification in the presence of two subscribing witnesses.

JOHN HENRY HETTINGER.
